[57]

ABSTRACT

A system to deliver a weighed charge to the mold box of a brick press so that the material is uniformly distributed in the mold is disclosed. Specifically, a weighed charge is conveyed to the mold by conventional means, but is distributed in the mold by the co-ordinated synchronous movement of both the lower press pad's downward motion and the reciprocating action of the charger during the charging sequence.

WEIGHED CHARGE SYSTEM FOR A BRICK PRESS

Many of the important properties of refractory bricks are governed by their bulk density, the control of which will depend on the success in feeding the same weight of uniformly mixed material to each mold box at each pressing. However, with many of the present brick press charging devices, segregation of the batch or uneven mold filling occurs which results in pressed brick of nonuniform properties. In addition, poor mold filling can result in an excess of entrapped air in the batch which can lead to problems such as cracking during and after the pressing cycle.

Accordingly, it is among the objects of this invention to provide a method and apparatus for uniformly filling a mold box with a refractory batch. It is another object of the invention to provide apparatus for modification of existing brickmaking presses, whereby brick of substantially uniform thickness, density and porosity can be made from a given refractory batch.

Briefly, according to this invention, there is provided apparatus for modification of a brick press, whereby brick of substantially uniform properties can be obtained from a given refractory batch. The apparatus includes means arranged to deliver accurately weighed quantities of granulated brick material to a mold charging system which evenly distributes the material in the mold box. An example of a mechanical brick press, which can be modified according to this invention, is shown, for example, in U.S. Pat. No. 987,124. This is sometimes called a Boyd-type press.

Other objects and further features and advantages of the invention will become apparent to those skilled in the art from a study of the following detailed description, with reference to the drawings. In these drawings:

FIG. 1 is a side elevation in partial section of apparatus according to this invention used with a brick press;

FIGS. 2 to 5 are partial cross sectional views of the mold box charging and pressing area illustrating four stages of the pressing cycle;

FIG. 6 is a hydraulic schematic diagram showing a series of solenoids and valves for actuation of the lower press pad situated in the mold box and for the charging cylinder; and,

FIG. 7 is an electrical diagram illustrating a means for synchronizing the operation of the press.

Those portions of a Boyd-type mechanical brick press which are shown in FIG. 1 include a worktable 15 provided with a rectangular molding cavity or mold box 16. The pressing of brick shapes in the mold box is accomplished by the movement of the upper and lower pressure plates or pads 18 and 19 attached to the upper and lower plungers 17 and 20, respectively. The lower plunger rests on a saddle plate 21 which in turn is disposed on a lower crosshead 22. The upper plunger is moved vertically by a crosshead (not shown) slidably mounted in guides (not shown) at opposite sides of the press frame (not shown). An exemplary construction for the upper portion of a brick press is shown in U.S. Pat. No. 2,893,101, and it is incorporated herein by reference.

In order to control the brick size in a conventional Boyd-type press, the operator would have adjusted, by a mechanical linkage, the depth of the mold for the fill

sequence by adjusting the height of the lower pad 19. Saddle springs in the lower crosshead provide an upward force on the saddle plate 21 and provide the clearance between the saddle plate and lower crosshead needed for mold fill depth adjustment. Herein lies one of the modifications of the Boyd-type press according to my invention. A hydraulic cylinder 24 is installed in the lower crosshead in place of the usual springs and mechanical linkage to control the downward motion to the saddle plate during the charging sequence. The hydraulic cylinder (saddle cylinder) 24 with an extended piston rod 23 and a mounting flange 25 at the rod end is mounted at the bottom of and on the centerlines of the lower crosshead 22. The top of the rod is connected to the saddle plate via a threaded hole 26. This arrangement allows the control of the travel of the lower pad which aids the brick mix in being uniformly distributed in the mold cavity.

The automatic batch feeding system comprises an automatic scale and hopper 10 which dispenses a desired amount of material 11 onto a conveyor comprising an endless belt feeder 12. The belt feeder delivers the material to the charger 14 and may be supported by the frame of the brick press or independently. The horizontal movement of the charger is controlled by the charger cylinder 13, which provides reciprocating movement of the charger back and fourth across the mold box which, in combination with the controlled downward movement of the lower pad, is the crux of this invention. The cylinder 13 contains a piston 30 and rod 31 which may be reciprocated by hydraulic fluid schematically illustrated in FIG. 6 or compressed air.

In FIG. 2, the lower pad 19 is raised to a relatively high position in the mold box. As the sequence is begun, the charger 14 distributes material 11 into the mold box 16 on the first stroke of the cylinder 13. The charger on the initial stroke delivers only a portion of the charge to the mold. After this first pass, the lower pad begins its descent which is synchronized with the reciprocating speed of cylinder 13 and mold box 16. The charger, on the first stroke, is moved horizontally so that the rear side has passed the mold centerline. At this time the saddle cylinder 24 lowers the saddle plate 21 slowly to provide more space for the material in the mold. At the same time the charger on its second stroke, moves horizontally until the front side has passed the centerline as shown in FIG. 3. Simultaneous lowering of the saddle and reciprocating motion of the charger is continued, and the mold is more completely filled. The sequential charging operation with synchronized lower pad positioning is continued until the mold is completely filled with layered portions.

In FIG. 2, the space 32 between the top of the crosshead 22 and the saddle 21 indicates that the saddle cylinder piston rod 23 is at the upward end of its stroke, whereas in FIG. 3 the saddle cylinder piston rod is near the lower end of its stroke. In FIG. 4, the mold has been completely filled, and the upper pad has descended and has compressed the material between it and the lower pad 19. The saddle 21 now rests on top of the crosshead 22. In FIG. 5, the pressed brick is being ejected by simultaneous upward motion of the lower crosshead through the controlled upward motion of the saddle cylinder rod. After the formed brick is ejected by being pushed off the lower pad by the front of the charger, the press cycle continues. The lower crosshead drops and, during its downward travel, the saddle cylinder

piston rod moves up elevating the lower pad to a relatively high position in the mold so that the first charger stroke partially fills the mold. The charger starts reciprocating strokes distributing material in the mold while the lower pad is simultaneously lowered by the saddle cylinder piston rod and so on.

The cylinders 13 and 24 which have double acting pistons may be actuated as shown by the schematic diagram of FIG. 6. The cylinders 13 and 24 contain pistons 30 and 34 and attached rods 31 and 35, respectively. For the cylinder 24, the hydraulic fluid is fed to the cylinder under pressure from a reservoir 36 by a conventional pump 37. The fluid passes through a directional control valve 38 for the controlling of the direction of motion of the cylinder piston (up or down). This action of this valve may be controlled by solenoid 39. From valve 38, the fluid passes into one of the flow control valves 40 or 41. Valve 40 controls the downward motion of the lower pad. Valve 41 controls the upward motion of the lower pad when the pressed brick is being ejected.

For the cylinder 13, the hydraulic fluid also passes through a directional control valve 42 controlled by a solenoid 43. However, here, the fluid passes directly into the cylinder since the mold box reciprocates rapidly with reference to the lower pad.

The hydraulic system could contain other components, i.e., pressure gauge, pressure relief valves, other solenoids, a fluid accumulator, filter and the like. However, these are not shown or discussed for the sake of brevity and since these are well known in the art. Many different hydraulic systems could be used to control the action of the pistons within the cylinders.

As mentioned previously, all of the steps in pressing brick shapes are synchronized for sequential operation. FIG. 6 illustrates an exemplary schematic electrical circuit for controlling the sequence of steps. A multiple cam timing switch is represented by three cams 50, 52 and 53. Each cam actuates valves 42, 38 and clutch 44, respectively, through their respective solenoids 43, 39 and 45. In practice, the cams may be mounted on a common shaft for rotation thereon. A voltage (V) is applied across the circuit from a source separate from that normally associated with the press. This circuit may be integrated with the press circuit and other components attached to the press. However, modifications would have to be made to the entire circuit as is well known in the art, and various other operative circuitry is possible.

When the operator at the press starts the switch for operation, all cams on the common shaft will rotate together. Cam 50 with the lead contact (a) will first close the switch and cause the charger 14 to move forward over the mold box 16. The opening of the switch will cause the charger to move back across the mold box to

its starting position. The repeated opening and closing of the switch throughout the half cycle of this cam provides the reciprocal movement of the charger.

Shortly after the contact (a) of cam 50 closes the switch, contact (b) of cam 52 closes a switch and causes the descent of lower pad 19. This descent is slow and continuous throughout an approximate half cycle of this cam.

When the descent is complete, contact (c) of cam 53 will activate a clutch on the clutch on the press which will in turn activate the mechanical linkages in the press to cause the upper pad 18 to descend and compress the material in the mold box. (For example, see U. S. Pat. No. 2,893,101.) The opening of the switch causes the pad 18 to retract.

At this point, contact (d) of cam 52 closes a switch which, through the hydraulic system, forces the lower pad upward to eject the compressed shape and position itself for the next cycle.

While illustrating my invention in connection with a Boyd-type mechanical press, it is readily applicable to other presses, whether mechanical or hydraulic type.

Having thus described the invention in detail and with sufficient particularity as to enable those skilled in the art to practice it, what is desired to have protected by Letters Patent is set forth in the following claims.

The embodiments of the invention in which an exclusive property or privilege is claimed are defined as follows:

1. In combination with a brick press having a mold box and a vertically movable upper press pad, means for accurately weighing quantities of granular material, means for charging said weighed material to the mold box by continuous reciprocal movement, a vertically movable lower press pad within the mold box, electrical means synchronized with the reciprocation of the charging means for lowering the lower press pad while the mold box is being filled by the charging means with a series of continuous reciprocating strokes, means for lowering the upper pad into the mold box after the lower pad has ceased descending to compress the granular material into a shape between the upper and lower pads, means for raising the upper pad and means for raising the lower pad to eject the compressed shape.

2. The combination of claim 1 which includes means for synchronizing sequential movement of the charging means, lower press pad and upper press pad.

3. The combination of claim 1 in which the vertical movement of the lower pad and the reciprocal movement of the charging means is provided by a double action piston contained within a pressure cylinder.

4. The combination of claim 3 in which the pressure is provided by hydraulic fluid.
